(57) CLAIM

The ornamental design for a caliper cover, as shown and described.

DESCRIPTION

FIG. 1 is a front elevational view of a caliper cover showing my design.

FIG. 2 is a top plan view of the caliper cover of FIG. 1.

FIG. 3 is a bottom plan view of the caliper cover of FIG. 1.

FIG. 4 is a rear elevational view of the caliper cover of FIG. 1.

FIG. 5 is a right side elevational view of the caliper cover of FIG. 1.

FIG. 6 is a left side elevational view of the caliper cover of FIG. 1.

FIG. 7 is a front elevational view of a second embodiment of a caliper cover showing my design; the sole difference being the front side defines a cut-out as shown.

FIG. 8 is a top plan view of the caliper cover of FIG. 7.

FIG. 9 is a bottom plan view of the caliper cover of FIG. 7.

FIG. 10 is a rear elevational view of the caliper cover of FIG. 7.

FIG. 11 is a right side elevational view of the caliper cover of FIG. 7; and,

FIG. 12 is a left side elevational view of the caliper cover of FIG. 7.
